OPERATING DEVICE FOR CLOSURES

Martin S. Kirkpatrick, Elmendorf, Tex.

Application March 9, 1937, Serial No. 129,890

5 Claims. (Cl. 39—25)

This invention relates to operating devices for closures such as gates, doors and the like of the sliding type and has for the primary object the provision of an efficient and inexpensive device of this character which may be easily actuated by a person to slide the closure either to open or closed positions without the person moving from a selected position of operation and includes means for checking the movement of the closure as it nears either its open or closed position to prevent said closure from stopping suddenly which might damage the closure or the parts of the operating device.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation, partly in section, illustrating a closure equipped with an operating device constructed in accordance with my invention.

Figure 2 is a fragmentary side elevation, partly in section, showing parts of the operating device occupying positions when the closure is in an open position.

Figure 3 is a sectional view taken on the line 3—3 of Figure 2.

Figure 4 is a sectional view taken on the line 4—4 of Figure 1.

Figure 5 is a fragmentary sectional view illustrating a pulley construction.

Figure 6 is a detail sectional view taken on the line 6—6 of Figure 1.

I have elected to show my invention adapted to a sliding type gate 1, however, the present invention is readily adaptable to other types of closures. Shown associated with the gate are vertically arranged posts 2 and 3 forming therebetween an entrance to be closed by the gate 1 and to be opened by the gate 1 moving in the direction of a post 4 located beyond the post 2. The posts are connected by a cross member 5, the height of which is such that vehicles and the like may pass freely through the entrance between the posts 2 and 3. A track 6 is connected to the posts in a plane below the cross member 5, however, at a height which will be sufficient to permit passing of vehicles and the like through the entrance defined by the posts 2 and 3. Hangers 7 secured to the gate 1 are provided with rollers 8 that travel on the track 6 so that the

gate may be made to slide freely to open and closed positions. The track 6 is of channel iron construction which will aid in excluding weather elements from the rollers 8. The upper portions of the posts are slotted and operating therein is a beam 9, one end of which is pivoted to the post 4, as shown at 10, while the opposite end projects slightly beyond the post 3 and has pivoted thereto a hanger or bracket 11 on which are journaled connected sheaves 12 and 13. The last-named end of the beam is connected to an operating lever 14 by a connecting rod 15. The operating lever 14 is pivoted on the post 3 adjacent the ground and its free end is pivotally connected to a pivotally mounted treadle 16 located adjacent the entrance defined by the posts 2 and 3.

A groove 17 is formed in the beam 9 and extends substantially the full length thereof to provide a guideway for one run of a cable 18. An other run of the cable passes over a pulley 19 journaled on the post 4 and a pulley 20 journaled on the pivoted end of the beam. One end of the cable is fastened to one end of the gate, as shown at 21. The cable as it leaves the guideway at the non-pivoted end of the beam passes over a pulley 22 journaled on the beam and also passes about the sheave 13 and is connected to the opposite end of the gate by a member 23.

A flexible element 24 is secured to one end of the member 5 and to a bracket 25 secured on the post 3. The flexible element 24 is disposed vertically and is passed about the sheave 13 so that said sheave will be rotated by the upward and downward movement of the free end of the beam 9. The sheaves being thus rotated will cause the gate to be slid open and closed. As the free end of the beam moves upwardly, the gate slides open and as the free end of the beam moves downwardly the gate slides closed. The pivotal movement of the beam 9 is caused by the manual actuation of the treadle 16.

A supporting structure 26 is secured to the post 3 and includes horizontally and vertically arranged members and secured to the horizontal member are pulleys 27 over which a flexible element 28 is trained. Pivoted on the supporting structure 26 are levers 29 and 30 located in the path of movement of the operating lever 14 and arranged above and below the latter. One end of the flexible element 28 is secured to the lever 30 and the other end of the flexible element has a weight 31 secured thereto. The flexible element 28 is secured to the lever 29. As the operating lever 14 moves upwardly to bring about

opening of the closure it engages the lever 29 lifting the weight 31 for the purpose of checking or retarding the movement of the closure towards said open position and on movement of the lever 14 downwardly to close the gate it engages with the lever 30 bringing about raising of the weight 31 and thereby checking or retarding the movement of the closure towards a closed position. It is to be understood that the operating lever 14 only engages the levers 29 and 30 as the closure nears its closed or open position.

What is claimed is:

1. A closure operating device including a closure mounted for sliding movement into either open or closed position, a supporting structure for said closure, a beam pivotally mounted on said supporting structure, sheaves journaled on the beam, means carried by the supporting structure to engage the sheaves for imparting rotation thereto by the pivotal movement of the beam, operating means connected to the beam for imparting pivotal movement thereto, and flexible means connected with opposite ends of the closure and engaged by the sheaves for sliding the closure by the pivotal movement of said beam.

2. A closure operating device including a closure mounted for sliding movement into either open or closed position, a supporting structure for said closure, a beam pivotally mounted on said supporting structure, sheaves journaled on the beam, means carried by the supporting structure to engage the sheaves for imparting rotation thereto by the pivotal movement of the beam, operating means connected to the beam for imparting pivotal movement thereto, flexible means connected with opposite ends of the closure and engaged by the sheaves for sliding the closure by the pivotal movement of said beam, and means for slidably mounting the flexible means on the beam.

3. A closure operating device including a closure mounted for sliding movement into either open or closed position, a supporting structure for said closure, a beam pivotally mounted on said supporting structure, sheaves journaled on the beam, means carried by the supporting structure

to engage the sheaves for imparting rotation thereto by the pivotal movement of the beam, operating means connected to the beam for imparting pivotal movement thereto, flexible means connected with opposite ends of the closure and engaged by the sheaves for sliding the closure by the pivotal movement of said beam, means for slidably mounting the flexible means on the beam, and means connected to said operating means for retarding the movement of the closure as the latter reaches near the limit of its movement.

4. An operating device for closures comprising a supporting structure, a closure slidably mounted on said supporting structure, a beam pivoted on said supporting structure, sheaves journaled on the beam, a flexible element secured to the supporting structure and engaging said sheaves to impart rotation thereto by the pivotal movement of the beam, a flexible element connected to the sheaves and to opposite ends of said closure, means slidably connecting said flexible element on said beam, means for supporting the flexible element on the supporting structure, and a treadle operated means connected to the beam.

5. An operating device for closures comprising a supporting structure, a closure slidably mounted on said supporting structure, a beam pivoted on said supporting structure, sheaves journaled on the beam, a flexible element secured to the supporting structure and engaging said sheaves to impart rotation thereto by the pivotal movement of the beam, a flexible element connected to the sheaves and to opposite ends of said closure, means slidably connecting said flexible element on said beam, means for supporting the flexible element on the supporting structure, a treadle operated means connected to the beam, and including a pivotally mounted lever, auxiliary levers pivotally mounted on the supporting structure and arranged in the path of movement of said first lever, a flexible element slidably mounted on the supporting structure and connected to said auxiliary levers, and a weight connected to one end of the last-named flexible element.

MARTIN S. KIRKPATRICK.
